ALCOHOL BURNER

Morris E. Solomon, New York, N. Y.

Application April 18, 1936, Serial No. 75,034

8 Claims. (Cl. 158—97)

The present invention relates to improvements in an alcohol burner and has for an object to provide an alcohol burner adjustable to provide different flame intensities.

5 A further object is to provide a control means for the burner which regulates the flame intensity and also acts to extinguish the flame when it is no longer desired.

10 A further object is to form the burner with a shield or casing which serves to retain heat and vaporize the fuel and which also serves to create a forced draft.

15 With the foregoing and other objects in view, the invention will be more fully described hereinafter, and will be more particularly pointed out in the claims appended hereto.

In the drawings, wherein like symbols refer to like or corresponding parts throughout the several views,

20 Figure 1 is a central vertical section of a burner embodying the features of the present invention.

Figure 2 is a top plan view of the same.

Figure 3 is a side elevation of the left side of the burner shown in Figures 1 and 2.

25 Figure 4 is a side elevation of a modified form of burner in which the relation of the flame control and the flame extinguisher is modified.

Figure 5 is a side elevation of a further modification of burner in which the shape of the casing has been changed.

Figure 6 is a side elevation of burner shown in Figure 5 looking at the left side thereof, and

Figure 7 is a side elevation of still another modification having a further modified flame extinguisher and flame control.

Referring now to the drawings and particularly to Figure 1 the burner comprises a fuel holder 10 filled with a suitable wick material 11 which is saturated with the alcohol or the particular fuel to be used. The wick is held in place by a cover 12 of a coarse mesh which is kept within the holder 10 by a ring 13 placed around the inside of the top of the holder 10. The holder 10 is set upon a tray 14 and the spherical shaped shield or casing 15 placed over the container and onto the tray 14. The spherical casing is open at the bottom to fit snugly about the container 10 and is adapted to fit on the tray 14 to form a seal with the upstanding flange 16 of the tray. The dome of the casing 15 has a section cut out to provide a burner tip 17. A circular band 18 is placed over the casing 15 and is pivoted at diametrically opposite points 19 and 20. Band 18 is slightly wider than the width of the burner opening 17 which permits a complete closing of

the burner tip, as illustrated in Fig. 2. Band 18 is pivoted some distance from its ends at 19 and 20 to provide swinging valves 21 for controlling the air supply ports 22 in the casing. The band 18 so pivoted may be used to cut off the air supply to the burner by covering the air ports 22 and the movement of the band serves to cover the burner tip 17 and extinguish the flame. For the purpose of moving the band a stem 23 and operating knob 24 are attached to the band at 10 the pivot 20.

It will be noted that due to the spherical shape of the casing 15 a free air circulation from the air ports 22 up through the burner tip 17 is permitted even when the fuel holder 10 is in place 15 as will be seen in Figure 1. When the fuel in the holder 10 is ignited primary combustion takes place just above the mesh cover 12. The flames thus produced travel along the spherical walls of the casing 15 to the burner tip where, due to 20 the great excess of oxygen, a secondary combustion takes place and the fuel is completely consumed in a blue or colorless flame. The flames which travel along the inner wall of the casing 15 rapidly heat the same and with the air ports 25 22 open a fairly rapid convection current of air is established which aids the primary combustion and produces a stronger flame. Heating the casing 15 also assists in vaporizing the fuel so that it is possible to produce very rapid burning 30 when such is desired. After the casing has been heated with the air ports 22 open the flame will grow with the increase of heat until it may become desirable to check the burning. This may be done by rotating the band 18 by means of the 35 knob 24 which is preferably made of wood or some other non-conducting material. The band 18 is rotated until the valves 21 begin to cover the air ports 22 with consequent checking of the flame. Further closing of the air ports 22 will 40 result in greater modulation of the flame until the desired adjustment is produced. It is also possible by continuing the rotation of the band to partially cover the burner tip so that further adjustment is possible. It will be observed from 45 Figure 3 that the valves 21 completely cover the air supply ports 22 before the upper part of the band 18 cuts down the burner tip 17. As a result of this the air supply may be completely shut off first and then if necessary the tip opening may 50 be decreased. Rotation of the band 18 to the vertical position results in completely covering the tip 17 and extinguishing the flame. The outer ends of the valves 21 are shaped to provide for complete coverage of the air supply ports 55.

and yet leave clearance between the valve and the flange 16 of the tray 14 as the band is rotated. It will also be noted that when it is desired to extinguish the burner quickly when it is completely open the extinguishing band 18 first covers the air supply ports 22 then the burner tip 17 so that first the air supply is completely shut off from the alcohol and all tendency of continued burning or smouldering of the wick is averted.

Referring now to the form shown in Figure 4, the cylindrical casing 25 has a dome-shaped top in which may be cut burner tip 17, as before shown. Fuel container 10 is set down into the tray 26 which supports the casing 25 upon an outstanding flange 21. The tray 26 in this form carries the air supply ports 28 at opposite points of its circumference. In this form the valves 21 and the band 18 operate about the same time so that air ports 28 are closed at the same time as the burner tip 17 is closed. The dome in this burner is a great deal higher than the top of the burner above described with the result that there is a greater air space between the top of the fuel holder 10 where initial combustion takes place and the burner tip 17 where the secondary or complete combustion takes place. One result of this is that there is a relatively large volume of heated air in this space which serves to increase the draft through the burner when the ports 28 are open. This form is not susceptible of such fine adjustments as the first form of burner due to the change in proportion of the extinguishing portion and the air supply valve portions of the band.

Referring now to the form shown in Figure 5, the casing 29 is mainly cylindrical and provided with the dome 30 which is flattened at its extreme upper portion as at 31. Referring to Fig. 6, the burner tip 17 is cut through this flat portion. In this burner the band 32 consists only of an extinguishing loop and the air ports 22 in opposite sides of the casing are always open. The dome shaped upper portion 30 (seen in Fig. 5) serves to increase the amount of air flowing through the burner and to increase thereby the amount of combustion taking place. Variation of the size of the flame is accomplished by cutting down the size of the opening of the burner tip. This form of the device is particularly useful where a narrow burner is needed as this does not take up the amount of space required by the spherical type and it is not as tall as the type shown in Figure 4. In many applications the amount of adjustment obtainable with this burner is satisfactory.

With reference to the form of burner shown in Figure 7, the casing 34 is cylindrical and is crowned by the dome shaped top 35 in which is cut the wide burner tip opening 36. The fuel container and the casing rest on the tray 33 and the air ports 22 are placed in opposite sides of the casing 34. The band 18 is pivoted to swing across the burner tip opening 36 and to carry the valves 37 for the ports 22. The loop of the band which travels across the burner tip opening is narrower than the greatest opening of the burner tip opening so that complete extinction of the flame is not possible but only reduction in the effective size of the burner tip opening. The valve portion 37 of the band flares outwardly toward the end so that ports 22 are closed about the same time as the loop of the band 18 passes across the burner tip opening.

All forms of burners above described have the

dome shaped top. It has been found that the flames at the top of the fuel container travel up along the inside of this top and this has a very pronounced effect in increasing the quantity of air drawn through the burner as well as heating up the burner and assisting in volatilizing the fuel.

It is obvious that various changes and modifications may be made in the details of construction and design of the above specifically described embodiment of this invention without departing from the spirit thereof, such changes and modifications being restricted only by the scope of the following claims.

What is claimed is:

1. An alcohol burner comprising a fuel holder, a casing enclosing said fuel holder the upper portion of which is spherical, a tray for receiving both holder and casing and having an outstanding flange to seal the bottom of the casing, said casing being spaced from said holder and provided with an air port in its lower section, the upper portion of said casing having a centrally located opening to act as a burner tip, a band pivoted on opposite sides of said casing to travel across said opening when rotated about its pivots, and a valve for said air port moving with said band across said air port, the length of said burner tip opening being less than the diameter of the fuel holder.

2. An alcohol burner comprising a fuel container, a casing about said container apertured at its bottom to fit over the container the top portion of which is dome-shaped, said top portion being provided with an opening to act as a burner tip, and said casing being provided with air ports at opposite sides thereof, a band fitting partly around said casing to cover said burner tip opening and said air ports, and said band being pivoted inwardly of its ends at opposite sides of said casing to provide a loop movable over the top of the casing to cover the burner tip opening and below the pivots a pair of valves for said air ports movable to close said ports, said loop and said valves moving simultaneously, said valves closing said ports before the loop covers the burner tip opening.

3. In an alcohol burner having a fuel container, a casing about said container comprising a body portion spaced away from said container and a dome shaped upper portion having a burner tip opening therein, said body portion having air ports at opposite sides thereof, a control band pivoted on said body portion providing a loop for restricting said burner tip opening, and valves for closing said air ports simultaneously when the band is rotated.

4. A burner for volatile fuel comprising, a fuel holder, a casing enclosing said fuel holder, said casing being spaced from the upper part of the fuel holder, and having a dome-shaped top, said top portion being provided with an opening therein to act as a burner tip, the area of said opening being considerably less than that of the upper portion of the fuel holder, said casing also being provided with an air port in its lower part, and a band having a width substantially equal to the width of the burner tip opening in the dome-shaped top, said band being pivoted to said casing to travel to a position over said burner tip opening, when rotated about its pivots, and a valve for said air port moving with said band across said air port for closing the same substantially simultaneously with the closing by the band of the burner tip opening.

5. An alcohol burner comprising a cylindrically-shaped fuel holder, a dome-shaped casing about said holder having an elongated burner tip opening in the top thereof, said casing being spaced away from said holder to provide an air space therebetween by which the flame from the fuel is passed out of the burner tip opening, said casing being provided with air port openings in its lower part, and means on said casing for simultaneous control of the burner tip and the air port openings.

6. An alcohol burner comprising a cylindrical fuel holder, a casing enclosing said holder and having a dome-shaped top in which is provided centrally thereof, an elongated burner tip opening, said casing being provided with air ports in its lower portion, said casing being spaced away from said holder to provide an air space therebetween by which the flame from the fuel is passed out of the burner tip opening, a band pivoted on said casing and adapted to gradually close, first the air ports and then the burner tip opening, said air ports being completely closed before the burner opening is closed and remaining closed while the burner opening is being closed.

7. A burner for volatile fuel comprising a fuel holder, a casing enclosing said fuel holder, said

casing being spaced from the upper part of the fuel holder and having a dome-shaped top, said top being provided with an opening centrally thereof to act as a burner tip, said opening being considerably smaller than the top of the fuel holder, said casing also having air ports in its lower part, and a band the width of which is substantially equal to the width of the opening in the dome-shaped top, said band being pivoted to said casing at opposite points and fully covering said opening when rotated about its pivots.

8. An alcohol burner comprising a cylindrically shaped fuel container for solid alcohol, an enclosing casing having a spherically shaped top, the spherically shaped top of said casing being spaced from the top of the container to provide a dome-shaped space therebetween, said top of the casing having an elongated opening cut centrally thereacross, said opening being widest above the central part of the container and tapering towards its ends, said opening in the casing acting as a burner tip, and a control band curved to conform closely to the shape of said top and pivoted to the casing so as to be movable to cover said burner tip and extinguish the flame, said band covering the entire burner tip opening when placed over the same.
